UNITED STATES PATENT OFFICE.

ALONZO J. ROBERTS, OF ST. LOUIS, MISSOURI, ASSIGNOR TO WILLIAMS PATENT CRUSHER AND PULVERIZER CO., OF ST. LOUIS, MISSOURI, A CORPORATION OF MISSOURI.

PNEUMATIC METAL-CATCHER.

1,306,775.

Specification of Letters Patent. Patented June 17, 1919.

Application filed March 1, 1919. Serial No. 280,007.

To all whom it may concern:

Be it known that I, ALONZO J. ROBERTS, a citizen of the United States, residing at St. Louis, State of Missouri; have invented certain new and useful Improvements in Pneumatic Metal-Catchers, of which the following is a specification.

This invention relates to certain new and useful improvements in pneumatic metal catchers, the peculiarities of which will be hereinafter described and claimed.

The object of my improvements is to provide means for separating pneumatically, metal, gravel, sand, and like heavy or foreign matter from the feed hopper in the supply delivered to feed mills, grinders, and similar machines.

My improvements relate to an air supply pipe with a flaring end adapted to deliver a regulatable current of air directly opposing a vertically descending stream of feed, so as to return the lighter particles over the top while the heavier particles drop and have reference to means for catching the medium heavy particles that are not light enough to be sucked over the top with the feed, nor heavy enough to drop to a pocket in the bottom of the air pipe; and allow of the passing of the heavier particles of the feed proper to the mill through a bypass and joining the main supply of feed proper passing over the top of said pipe; and have reference to other points hereinafter described and claimed.

In the accompanying drawing on which like reference letters indicate corresponding parts, Figure 1 represents a front view of a mill and fan having my improvement applied thereto; Fig. 2 a side view of said mill and fan, with my improved catcher shown in section, and part of said mill and fan being broken away; and Fig. 3 is an enlarged detail view of a part of my catcher and partly in section.

The letter A designates a mill of any suitable construction, and B a fan, such as a flywheel fan mounted on said mill, and connected thereto by a pipe C in order to produce a suction through the mill and through the feed inlet D at the top thereof. Pivoted rotary hammers E, Fig. 2, rotate in the direction of the arrow past the said feed opening. A cut-off slide F varies the size of this opening for the inlet of feed.

Above this inlet for the main supply of

feed to said mill, is mounted a vertical drum G, the outlet H of which registers with the inlet opening to the mill, and the inlet I to said drum at the top is connected by a pipe J to a feed hopper A', or other means for delivering the feed to said drum.

The outlet and inlet of said drum are reduced in size by cone ends of the drum, and the delivery pipe J is preferably provided with a slip extension L, the bottom end of which is inside of the drum and has a flaring downwardly inclined cone K, practically the size of said drum G and adjustable up and down therein. A strip M with a pin passing through holes in said pipe J according to the adjusted position of the slip pipe, maintains the adjusted position thereof.

In the upper part of said drum is located a registering cone N opposing said cone K but of lesser diameter at its periphery, and forming the upper end of a centrally located air pipe O, having its lower end P turned outward and downward to pass outside of said drum G, and form a pocket Q at the bottom thereof to which access is had by means of a slide R. In the upper side of the lower part of this pipe P is an air valve S, by which air is admitted from outside into the inclined pipe P and sucked upward through the pipe O and downward outside the cone N, by the air suction produced through the mill inlet D by the exhaust fan B. This central pipe O and its extension P are preferably rectangular, and the flaring end provided with a downwardly inclined edge N is preferably round as it is adapted to register with the upper cone K and the drum G inclosing said cones.

The stream of feed descending vertically from the hopper A' through the pipe L, meets the upwardly acting current of air entering through the valve S and passing upward through the pipe O directly in line with and opposing the delivery pipe L, and its vertical descending direction is changed to an upward and outward direction over the downturned edge N of the flaring end of the pipe O and then downward inside the drum G to the inlet D of the mill as to the lighter particles therein; but the heavier particles, such as nails, descend through the pipe O into the pocket Q at the bottom of the pipe P. The valve S allows of regulating the amount of the air entering through the pipes P and O. The velocity

or force of the air over the top of the cone N, is regulated by adjusting the upper cone K to vary the distance between said cones. Thus the lowering of the cone K will produce a smaller opening between said cones, and the air will be drawn therethrough under the suction of the fan, with a greater velocity, and will act with greater lifting force upon the particles of feed delivered from the pipe L and its extension into the flaring end of the pipe O.

For the heaviest foreign particles, such as nails and other metal pieces, this pocket Q is sufficient, but I have found it advisable to provide another means of separating particles that are of medium weight from the feed proper, when such medium particles, such as lighter particles of metal or gravel and sand, are contained in the feed supply. I therefore provide in the pipe O a lateral extension or inclined leg T, communicating by an opening U with the pipe O, and preferably rectangular in order that the edge V at the lower intersection may be straight and horizontal. The pipe T inclines downward, and outside of the drum G is widened horizontally as shown in Fig. 1 at W, to a connection with a reversely inclined rectangular box Y, that communicates with the mill through another mill inlet d. This box Y has a pocket 2, by which means the medium heavy particles passing over the edge V and down the pipe T and flaring end W, are caught as they drop into the box Y as indicated in Fig. 2. A slide 3 allows of the cleaning of said box or pocket from the accumulated particles.

In the pipe T and outside of the drum G is a cut-off slide 4 by which the size of the pipe T is varied, or maybe closed entirely. When the slide 4 is closed, all the air admitted by the air valve S passes upward and over the flaring end of the pipe O and downward with the lighter particles of feed to the feed inlet D. Also another pocket 2' for medium particles is formed in the pipe T above the cut-off slide. When the slide 4 is open more or less, a part of the air entering the valve S is deflected through the by-pass formed by the pipes T, W and box Y, to the mill inlet d. Thus medium heavy particles, not normally sucked over the top of the cone N and yet light enough to be acted on by the air current through the valve S, are deflected over the edge V into the by-pass and are caught in the pocket 2. The feed that may be taken along with the metal particles, will proceed onward through the inlet d and join the main supply delivered by the pipe H to the inlet D.

In the box Y are provided saw tooth projections 5 from the bottom of the box, and inclined toward the hammers E, so that should any particles of metal, such as broken pieces of the hammers, be driven outward

by the hammers into the box Y they will be caught by said projections 5 or by the pocket 2 beyond said projections.

I have found that when operating upon lighter material than screenings, the feed proper passing through the by-pass with the medium heavy metal particles does not lodge with the metal in the pocket 2 but is carried onward to the mill. With feed that is heavier than screenings, the pocket 2 may fill up as indicated by the dotted line Fig. 2, but the bed of material thus formed, together with the projections 5, will catch the medium heavy particles descending through the by-pass.

The cut-off slide 4 in the leg which is likewise subject to air suction, varies the relative proportion of the suction in said leg to the suction over the top of the flaring upper end, and therefore the relative amount of feed that may be taken through the pipe T and the communicating extension W and the box Y to said mill. While I have described the space between the top cone N and the slip cone K at the drum inlet, as being varied by adjusting the upper cone, this space between the flaring upper end and the inlet for the feed may be varied by other means than by adjusting the cone N as a slip cone extension of the pipe L.

The square or rectangular pipes O and T forming the horizontal intersecting edge V, are preferably of this form in order to provide an edge of uniform height to secure uniform elevation or deflection of the medium light particles and metal over said edge V.

By means of the two adjustments of the velocity of the air admitted through the valve S,—that is, the velocity between the flaring upper end and the feed inlet above, and the velocity over the edge V at the intersection of the inclined pipe or leg T and the vertical pipe O,—I am able to obtain a separation of metal and other foreign substances in the feed, whatever the relative proportion of weight between the feed proper and said foreign particles or substances. Thus when operating on oat hulls which are very light, the air valve S is only slightly open, and the amount of air required to carry the hulls over the top of the cone N while allowing the foreign particles to drop down in the catcher Q receiving the heavier particles and the medium to be deflected into the pipe T and caught in the secondary pocket 2, can readily be adjusted; and similarly with other feed of different relative proportions as to the weight of the foreign substances and the weight of the feed proper.

I claim:

1. A pneumatic metal catcher comprising a drum having a top feed inlet opening and an outlet opening subject to air suction, a pipe having a flaring top centrally disposed

below said inlet and having its lower end extended outside said drum and forming a pocket, an air regulating valve in the outside part of said pipe, and means to vary the size of the space and consequently the air velocity between said flaring end and the top inlet.

2. A pneumatic metal catcher comprising a vertical drum having a top feed inlet opening and a lower outlet opening subject to air suction, an adjustable pipe having a flaring cone bottom mounted in said inlet, a pipe having a flaring cone top centrally disposed below and matching said adjustable cone bottom, and having its lower end extended outside said drum forming a pocket, and an air regulating valve in the outside part of the latter pipe.

3. A pneumatic metal catcher comprising a vertical drum having a top feed inlet and a lower outlet subject to air suction, a rectangular pipe having a flaring top centrally disposed below said top inlet, and having a bent-out lower end extended outside said drum forming a pocket, an air regulating valve in the outside end of said pipe, and an inclined leg intersecting said rectangular

pipe below its flaring top and opposite said bent-out lower end, and a reversely inclined box at the lower end of said leg forming a secondary pocket and having an outlet subject to air suction, whereby the heaviest particles are caught in the first named pocket and medium particles pass through the bypass to the secondary pocket.

4. A pneumatic metal catcher comprising a vertical drum having a top feed inlet and a lower outlet subject to air suction, a rectangular pipe having a flaring top centrally disposed below said top inlet, and having a bent-out lower end extended outside said drum forming a pocket, an air regulating valve in the outside end of said pipe, an inclined leg intersecting said rectangular pipe below its flaring top and opposite said bent-out lower end and likewise subject to air suction, and a cut-off valve regulating the suction through the leg with regard to the suction over the top cone of the first named pipe.

In testimony whereof I have affixed my signature.

ALONZO J. ROBERTS.
